UNITED STATES PATENT OFFICE.

JOSÉ BOSCH, OF BARCELONA, SPAIN, ASSIGNOR TO SCOTT AND WILLIAMS, INC., OF NEW YORK, N. Y., A CORPORATION OF MASSACHUSETTS.

STRIPING ATTACHMENT FOR KNITTING MACHINES.

Application filed July 12, 1923, Serial No. 651,094, and in Spain October 14, 1922.

My invention relates to circular knitting machines having revolving needle cylinders and is an attachment for making vertical stripes in the fabric produced on such machines. One object of my invention is to produce an attachment which is both simple and adaptable.

In the accompanying drawings, I have shown my mechanism applied to one of the well known Scott and Williams type of seamless hosiery machines.

Fig. 1 is an elevation of the left side of the head of a machine showing my attachment installed thereon;

Fig. 2 is a front elevation of sufficient of the head of the machine to show how my mechanism is attached;

Fig. 3 is the same as Fig. 2 with my bobbin stand swung into operative position; and

Fig. 4 is a plan view of the mechanism controlling the swinging of the bobbin stand.

In fabric made by my attachment supplementary yarns of the desired color or colors are wrapped around the needles which are to knit the stripe or stripes and these striping yarns are knit in with the ordinary yarn, the striping yarns being knit on the outside of the fabric so that the stripe will show.

Referring now to the drawings, the machine has a bedplate 1, a revolving cylinder of needles 2 and a latch ring 3 as usual. Projecting upward from the latch ring 3 are columns 4 and 5 which unite in a jaw 8. A bobbin stand 7 is suspended from this jaw 8 by means of a sleeve bearing 6 pivotally swung in the jaw 8 by two short pins 9, a shaft 10 inside the sleeve bearing 6 carrying the bobbin stand 7. The sleeve bearing 6 is from front to rear of the machine so that the bobbin can swing to the right of perpendicular (see Fig. 3). By means of the bevel gear 12 on the shaft 10 and the gear 13, driving gears 14, 15 and the shaft 16 the bobbin stand can be rotated at a constant speed whether perpendicular or swung to the right. It should be noted that the bevel gear 12 is located close to the pivot pins 9 and that the slight relative movement of the bevel gears 12, 13 due to the tilting of the bobbin carrier is accomplished without disengaging the gears by cutting the teeth of gears slightly deeper and having them engage more deeply. The shaft 16 can be driven from the main shaft

(not shown) in the manner shown in the Scott Patent 1,282,958, but in any case the needles 2 and the bobbin stand 7 should make the same number of revolutions per minute.

The bobbin stand 7 carries a number of vertical bobbins 17 each adapted to hold the supplementary yarn for a vertical stripe. In the drawings I have shown yarn arms 18 and yarn guides 19, the latter being designed to offer the yarn to the needles. These yarn guides 19 are arranged on the lower part of the bobbin stand on a circle of smaller diameter than that of the cylinder needles 2 and when perpendicular are at a height about opposite the top of the needles when raised to receive the yarn.

In making stockings it is not desirable to have stripes on the sole or heel of the foot and on some other parts. The mechanism which I shall now describe makes it possible to knit stripes on only one side or part of the tube, on all sides of the tube, or to stop making stripes entirely for any number of courses. The bobbin stand shaft 10 extends above the bevel gear 12 and has on its upper end a concentric disk 22 and an eccentrically mounted disk 23. Beside these two disks is a slide 27 horizontally movable in a guide 28 and controlled by a rod 29, and a bell crank lever 30, and a rod 31 connected thereto. (Fig. 1.) On the lower end of the rod 31 is a roller 32 adapted to move over the surface of cam 33 on the main pattern drum 34 and thus move the slide 27. There are tension springs 35 and 36 fastened between the slide 27 and the guide 28, and the guide 28 and the shaft 10.

On the slide 27 facing the disks 22 and 23 are short cams 24, 25 and 26, cams 24 and 26 being on a horizontal line with the concentric disk 22 and cam 25 on a horizontal line with the eccentric disk 23. It will be apparent from an examination of the positions of the three short cams 24, 25, and 26 (Fig. 1) that the drum cam 33 can move the slide 27 and bring any one of the three short cams opposite the disks 22 and 23. As seen in Fig. 1 the main pattern drum revolves clockwise and the cam 33 is a two step cam.

The cam 26 is low (Fig. 4) and when this cam is in engagement with disk 22 the bobbin stand is perpendicular (Fig. 2). When cam 25 is pushed into engagement with the eccentric 23 the bobbin stand is swung to

the right and revolution of the shaft 10 causes the striping yarn guides to oscillate between a position in which the guide nearest the needle circle is a short distance inside the latter, to operative position, when the circle of striping yarn guides just overlaps the needle circle as shown in Fig. 3. However, when the short cam 24 is in engagement with the concentric disk 22 the bobbin stand is held steadily in operative position so that the yarn guide circle just overlaps the needle circle.

For the purposes of illustration, I will now describe the operation of my attachment 15 when making a striped stocking.

When the welt of the stocking is being knit if no vertical stripes are desired the roller 32 mounted on the rod 31 rests on the high surface of the drum cam 33, the short 20 cam 26 is in contact with the concentric disk 22 and the bobbin stand and striping yarn guides hang perpendicularly as shown in Figures 1 and 2.

When about to begin knitting the striped 25 leg portion the roller 32 rides down off the high part of the cam to a low or intermediate position, which causes the slide 27 to bring the cam 25 opposite the eccentric disc 23. This movement is so timed that the low side 30 of the eccentric disc 23 is opposite the cam 25. The needle cylinder 2 and the bobbin stand shaft 10 now make half a revolution and the eccentric disc tips till the yarn guide circle just overlaps the needle circle. At 35 this moment the main pattern drum is racked again, the roller 32 drops down onto the surface of the drum and the slide rests on the surface of the main pattern drum 34 and the slide 27 is pulled forward under the influence 40 of the spring 35 till the short cam 24 engages the concentric disk 22. This holds the bobbin stand and striping yarn guides to the right till the yarn guide circle just overlaps the needle circle. As the yarn guides 45 revolve they are adjusted to cross the circle of needles just ahead of the corresponding striping needles. The striping yarn comes from inside the needle circle and lies across the path of the raised needle or needles 50 which is moving faster than the striping yarn guide because it is moving in a larger circle. The needle or needles therefore pass the 55 yarn guide, the yarn guide crosses back inside the needle circle as the two circles revolve and the thread is thus wrapped around the needle. Each group of needles which is to make a stripe has its corresponding bobbin and yarn guide and is fed as described. It will be noted that each striping yarn is 60 held on the inside of the needle circle at the sinker after the striping has once commenced, thus insuring accurate floating of the yarn around the needle.

At the heel of the stocking it is of course 65 desirable to stop the stripes on the heel side

of the stocking but to continue them down the instep. This is done by the roller 32 riding up the front face of cam 33 to an intermediate position, thus withdrawing the slide 27 till the short cam 25 is in contact with the eccentric disk 23. As the shaft 10 revolves, this eccentric disk bearing against the short cam will cause the bobbin stand and yarn guides to oscillate between the position in which the guide nearest the needle circle is 70 a short distance inside the latter and the position in which the striping yarn guide circle just overlaps the needle circle—as in the case of short cam 24 engaging the concentric disk 22. Since the yarn guides can 80 wrap the striping yarns around the needles only when the yarn guide and needle circles overlap as described, it will be apparent that according to the shape of the eccentric disk 23 some or many of the striping yarns will 85 not be knit into the stocking. The movements just described preferably take place for a few courses just making the heel. When actually going into the heel the roller 20 90 95 100 105 110 115 120 125 130 135 140 145 150 155 160 165 170 175 180 185 190 195 200 205 210 215 220 225 230 235 240 245 250 255 260 265 270 275 ed to swing said bobbin stand from the concentric position in which the yarn guides can not feed yarn to the needles, to a position in which the yarn guides and needle cylinder are in operative association.

4. In a striping attachment for a circular knitting machine having a revolving needle cylinder, revolving yarn guides arranged in a circle of smaller diameter than the circle of cylinder needles, said yarn guides being adapted to be swung as a unit till their circle overlaps the needle circle and then feed yarn to the needles substantially as described.

5. In a circular knitting machine having a revolving needle cylinder, a bobbin stand adapted to revolve at the same angular speed as the needle cylinder, and yarn guides mounted on said stand in a circle of lesser diameter than the circle of cylinder needles, in combination with means adapted to shift the position of the axis of the stand and thereby cause said yarn guides to wrap yarns around the needles, substantially as described.

6. In a circular knitting machine having a revolving needle cylinder, a revolving bobbin stand, bobbins and corresponding yarn guides on said bobbin stand, in combination with a shaft for said bobbin stand, concentric and eccentric disks on said shaft, a horizontal slide, and cams on said slide adapted to bear against said disks and swing said bobbin stand substantially as described.

7. In a circular knitting machine having a revolving needle cylinder and a pattern drum, a revolving bobbin stand within said cylinder, bobbins and corresponding yarn guides on said bobbin stand revolving with lesser linear velocity than the needles, a shaft for said bobbin stand, a horizontal slide and means associated with said shaft and slide to swing said bobbin stand, in combination with means controlled by the main pattern drum adapted to control the swinging of said bobbin stand.

In testimony whereof I have signed my name to this specification,

JOSÉ BOSCH.
